UNITED STATES PATENT OFFICE

DRIER

Heyman Rosenberg, New York, N. Y.

Application June 17, 1930. Serial No. 461,762

7 Claims. (Cl. 34—34)

This invention relates to improvements in drying apparatus, and has as its essential object the effective removal of moisture from relatively small articles of manufacture in an expeditious, inexpensive, and harmless manner.

A more detailed object is the effective drying of such articles without loss of surface-finishing substances for such articles.

A still further object is the thorough penetration of a mass of the articles being treated for eliminating moisture from interior portions as effectively as from more exposed portions without agitation of the articles.

With these and further objects in view as will in part hereinafter become apparent and in part be stated, the invention includes a hopper or like appropriate drying-agent container, a foraminous work container therein, a discharge for the work, and intake and exhaust means for the drying agent to and from the former container.

The invention also includes in such an apparatus a foraminous, pivotally-mounted bottom section for the work container and means for swinging said section to and from a closed position with respect to the work container.

The invention also comprises certain other novel constructions, combinations, and arrangements of parts as subsequently specified and claimed.

In the accompanying drawings,—

Figure 1 is a view in side elevation of a drier embodying the features of the present invention, parts being broken away and parts being seen in section.

Figure 2 is a view similar to Figure 1, the plane of observation being at right angles to that of Figure 1, and the hot blast pipe being seen broken away.

Figure 3 is a top plan view of the parts seen in Figures 1 and 2, the hood being indicated in dotted lines in its open position.

Referring to the drawings by numerals, 1, 1 indicate any appropriate frame, standards or other support on which is mounted the circulation chamber 2, which is hopper shaped and has its upper end closed by a cover plate 3. As illustrated, and as preferred, the upper portion of the container or hopper 2 is circular in cross section, and the cover plate 3 is an annulus rather than a disc, since it is centrally apertured, and a reticulated work container or inner hopper 4 is fixed to and depends from plate 3, the upper end portion of hopper 4 extending through plate 3 and being provided with a mar-

ginal ring 5 preferably of angle bar construction having a horizontal flange overlapping plate 3 and fixed thereto by screws or like appropriate anchorage devices 6. The inner peripheral portion of cover plate 3 is preferably offset or rabbeted in its upper surface to accommodate the outstanding flange of ring 5 while allowing the upper surface of said flange to lie substantially flush with the upper surface of the plate 3. Chamber or hopper 2 thus forms a surrounding casing for container 4.

A hood 7 rests on the plate 3 and surrounds the area immediately above the upper end of work container 4. A handle 8 is preferably provided for facilitating manual manipulation of the hood 7. Hood 7 converges upwardly to receive the lower end of a hot blast conduit or pipe 9 leading to and discharging in the upper end of the hood 7 from any appropriate source of hot air under pressure or like drying medium, which source is not illustrated, but may consist of any appropriate or acceptable furnace, such as a gas heater and blower, or an electrical heater, or other means of providing hot air or like hot gas under pressure. Fixed to and standing from the plate 3 at one point is a standard 10, the upper end of which terminates in a ring 11 to which the oncoming section of the hot blast pipe 9 is fixed. That section of the pipe 9 between the ring 11 and hood 7 has a slip joint into the hood and is hinged to ring 11, as by ears 12, 12, carried by the section of hot blast pipe, and ears 13, 13 outstanding from the ring 11 and pivotally connected to ears 12 by pintle 14. Thus, the hood 7 and the section of pipe 9 connected with the hood are adapted to be swung on the hinged connection with ring 11 from the full line position of Figure 1 to the dotted line position thereof and return to afford opportunity for the delivery of a fresh charge of work to the container 4. As hood 7 is preferably of cast metal, its weight is, of course, not sustained by hinge 12, but instead the hood is lifted manually and swung across plate 3 to and from the open position as seen in dotted lines in Figure 3. Of course, during operation, the supply of hot blast through pipe 9 will be cut off by an appropriate valve, not illustrated, before the hood 7 is swung to its open position, which is the dotted line position in Figure 3, and will be turned on again after the hood has been returned.

The plate 3 is preferably made of two semi-annular sections as seen in Figure 3, and the pressure container or hopper 2 is provided at 110

its upper edge with an outstanding flange on which plate 3 rests and to which the sections of said plate are preferably detachably fixed, as by appropriate bolts 15, 15 penetrating the 5 plate 3 and threading into the outstanding flange of container or hopper 2.

The lower portion of hopper 2 converges to provide the hopper effect and preferably varies in cross section from the circle of the upper 10 portion of the hopper to a square or quadrangle at the lower portion of the hopper.

The inner or work container 4 likewise is circular in cross section at its upper portion and converges downward to a lower end portion 15 which is substantially square in cross section. The lower margin of the hopper or inner container 4 is bordered by a reenforcing plate 16 and closed by a foraminous bottom section or trap 17, the latter being carried by a cross shaft 20 18 extending through and journaled in bosses 19, 19 outstanding laterally from hopper 2.

The outer container or hopper 2 converges downwardly to a lower end portion 20, which terminates in a discharge chute 21. The lower 25 end portion 20 is spaced below the lower end of the inner or work-containing hopper 4 a distance sufficient to allow the required swinging movement of the bottom section or trap 17, and the area through which the section 17 swings 30 is preferably surrounded or enclosed for foraminous walls 22, 22 fixed to the bottom portion or converging portion of the work container 4 and extending down and preferably detachably fixed to inner portions of the bottom 20 of hopper 2. The said walls 22 effectively confine 35 discharging articles of work against dislodgment out of the path of discharge.

An operating lever or handle 23 is detachably mounted on an extended portion of shaft 18 40 and connected thereto against relative rotation, so that, when the handle or lever 23 is swung, the shaft 18 will be likewise oscillated. The upper end of lever or handle 23 is preferably provided with an appropriate grip 24 to which 45 is pivoted a trip lever 25 engaging a detent plunger 26 located to detachably enter and interlock with an appropriate aperture in a retaining plate 27. Trip lever 25 is stressed by an appropriate contractile spring 28 for constantly subjecting the detent pin 26 to a stress tending to retain the pin seated in the recess in plate 27. Pin 26 extends through lever 23 from trip lever 25 to plate 27. Trip lever 25 is so located with respect to grip 24 as to be 50 naturally grasped when the grip 24 is engaged by the hand of the operator. Thus, in substantially one action the operator grasps trip lever 25, releases detent pin 26, and swings the lever 23 for rocking shaft 18 and thus swinging the bottom section 17 from its closed or upper 55 position to its open or lower position, and as soon as a supply of work being treated has discharged by gravity from the bottom section 17, the operator swings lever 23 back to the full line position of Figure 1, and the parts are ready for a further charge.

Chute 21 is formed at its under face with a discharge opening 29 communicating with a discharge pipe 30. A foraminous plate 31 covers the opening 29 so as to prevent passage of articles of work into the opening 29. It will be observed that the opening 29 and its discharge pipe 30 are of considerably less cross sectional area than that of the intake or blast supply pipe 32, so that the incoming heated medium, while

free to constantly exhaust through pipe 30, cannot escape as fast as it enters, and thus an appropriate pressure is maintained within the circulation container or hopper 2. The fact that exhaust can continue to occur insures constant movement of the contained air. Also, the location of the discharge opening 29 affords opportunity for ready drainage of any moisture dripping from work to the bottom 20 of hopper 2.

The lower end of the discharge chute 21 is 80 closed normally by a door 32, pivoted at 33, and counterbalanced at 34 for being maintained gravity closed. The counterbalance, however, is sufficiently light to allow the door to swing open to the dotted line position of Figure 1 when the door is struck by a batch of discharging work. The work discharged may be delivered to any appropriate means of distribution, one form of which consists of a container 35 disposed 85 beneath the chute 21 and adapted to be manually removed and replaced. Any other appropriate form of conveyor may be employed at this point when and as found desirable.

In operation, the handle 8 is grasped and the hood 7 swung from the closed position shown in 100 full lines in Figure 3 to the open position indicated in dotted lines. A batch of work is then dropped into the work container or inner hopper 4 with the lever 23 in its upright position and the bottom section 17 therefor closed against the 105 lower end of the hopper 4. The hood 7 is then swung back to the position closing hoppers 2 and 4, and the hot blast is turned on through supply pipe 9. The advancing hot air or other gas passes down through the foraminous hopper 110 4 and out through the various openings thereof into the hopper 2 and down toward the exhaust or discharge opening 29. As much of the hot air as can do so escapes through the discharge opening 29, the balance remaining and creating 115 a pressure within the hopper 2 and causing circulation of air therein. The work located in the hopper 4 is thoroughly penetrated by the hot air and the moisture picked up from the articles of work, leaving the work in a dry and 120 satisfactory condition. Such work may, for instance, be articles which have just been subjected to a galvanizing bath or to other treatment for improving or increasing surface resistance to rust or other injury, and the passage 125 of the air will remove the moisture from such articles without in any way injuriously affecting the substances present on the surface of the articles incident to such treatment. The removal of some of such substances by moving parts 130 of driers requiring movement is an objection which does not inhere in the present improved apparatus. After the batch or quantity of work has been dried to the extent required, which will be readily determined by test for each particular 135 kind of work, the operator releases the batch from the hopper 4 by manipulating the lever 23, as above described, and the batch discharges by gravity from bottom section 17 in its lowered position. The discharging work striking door 140 32 swings the door open and is thereby left free to descend into the container 35 or onto any appropriate conveyor. As soon as the work has escaped, the door 32 swings back by gravity under the influence of the counterbalance 34 to 145 the closed position, whereby the circulating hopper is again sealed against the escape of air except through the discharge opening 29. Of course, the operator may and usually will cut off the air supply from the intake pipe 9 while 150

discharging work from hopper 4 and while supplying another batch of work thereto.

While discharge opening 29 is essentially for the escape of air, it also serves, as above indicated, for drainage of free moisture, and as the work must not contact with free moisture while discharging, the exit 29 is formed first as a thin chamber 29' at the juncture with the chute 21, which chamber merges into the main body of the discharge pipe 29. Chamber 29' extends upward, as clearly seen in Figure 1, far enough to underlie the lower portion of bottom section 17 when the latter is in the discharging position. It should be understood, of course, that all of the free moisture will have drained off from the work sometime before section 17 is to be lowered for discharging, and that the free moisture in escaping finds entrance to the discharge pipe 29 at the extreme upper edge of chamber 29'; but if any free moisture should for any reason linger in chamber 29' up to the time of the discharge, the lapping of the free portion of bottom section 17 past and below the upper part of chamber 29' insures discharge of work only on thoroughly dry walls, including the perforated plate or screen 31.

It is noted that the blast from pipe 9 enters through the center of the top of the hood 7 and is, therefore, directed down upon the mass in the hopper 14 chiefly centrally thereof, and thus portions of the current which spread cannot escape into hopper 1 except through hopper 4. Though some of the air current passes laterally out of hopper 4, most of it penetrates the mass of work, and that portion which escapes laterally is circulated downward and beneath the work in contact therewith. The mounting of the foraminous work container 4 within the imperforate housing or hopper 1 is such that the air escaping at a less rate through exhaust 29 than the rate of entrance through intake pipe 9 will have opportunity to freely circulate about all sides and beneath the work container 4, and, therefore, movement of the drying air in contact with the contained work on all sides and every angle is assured.

The apparatus is well adapted for drying numerous forms of small articles, such as nuts, bolts, screws, rivets, buckles, buttons, and the like, or any other small articles which are moistened either in the course of construction or in being completed and require expeditious drying.

The weight 34 for the door 32 is sufficient for normally maintaining the door closed against the pressure of the contained air so as to prevent leakage and allow escape of air to occur solely through the discharge 29.

In the manufacture of small articles, difficulty has been experienced in preserving the same against rust during that period between the time of manufacture and the time of delivery to the consumer. Such articles as screws, bolts, and the like, if rusted on the shelves of the jobber or retailer are not as satisfactory to the consumer and not as readily saleable. It has been proposed to coat, laquer, oil or otherwise treat such articles to provide temporary protection against oxidation, and in the use of the present improved drier I propose to treat such small metal articles with an oleaginous solution destined to effectively temporarily protect against rusting, but one of the problems incident to such treatment is the removal of the moisture from the surface of the articles after treatment without removal of the coating solids. Driers which

require agitation or appreciable movement of the articles to enhance or render effective the drying action tend to throw off the coating substances with the moisture and thus to leave the articles in practically the condition they were in before treatment in the oleaginous bath. The present improved apparatus enables the removal of the moisture in an effective manner without loss of any of the preserving materials from the surface of the articles of work. In the preferred mode or art of drying such articles of work, the articles are held in the reticulated or inner container in a stationary condition while the heated air or other hot blast descends directly upon them, and a certain portion of such blast is allowed to move on down and out through the exhaust opening. The exhaust, however, being too small for exhaustion at the rate of inflow, a pressure is set up which plus the advancing movement incident to a partial exhaust causes the drying medium to advance through the mass of work and effectively dry the whole mass including innermost articles even though the container 4 is completely filled with work, and this drying operation is accomplished expeditiously and with no tendency whatever toward removal of the coating or preserving materials on the surface of the work.

What is claimed is:—

1. The combination of a reticulated container for work to be dried including a reticulated bottom section for the container and a casing, surrounding the container a pivotal support for said bottom section, means for swinging the bottom section on said pivot to and from a position closing the bottom of the work container, means for causing a gaseous heating media to approach and contact with the work from all directions, and means for creating positive or static pressure of the heating media against the work while permitting movement of the media relative to the work.

2. The combination of a hopper imperforate save for an exhaust opening, intake and discharge openings, means for delivering a hot blast into the hopper through the intake opening under pressure generated preceding the intake, means for normally closing the discharge opening against leakage of the pressure of said blast, and a work container disposed in the path of the blast, the work container being located above the discharge opening and having a movable wall adapted to be moved from a position closing the work container to a discharging position directing work by gravity toward the discharge opening.

3. The combination of a hopper imperforate save for an exhaust opening, an intake, and discharge openings, means for delivering a hot blast into the hopper through the intake opening, means for normally closing the discharge opening against leakage of the pressure of said blast, and a work container disposed in the path of the blast, the work container being located above the discharge opening and having a movable wall adapted to be moved from a position closing the work container to a discharging position directing work by gravity toward the discharge opening, and a cover grid for the exhaust opening located to receive and direct discharging work to the discharge opening.

4. The combination of a hopper imperforate save for an exhaust opening, an intake, and discharge openings, means for delivering a hot blast into the hopper through the intake open-

- ing, means for normally closing the discharge opening against leakage of the pressure of said blast, and a work container disposed in the path of the blast, the work container being located above the discharge opening and having a movable wall adapted to be moved from a position closing the work container to a discharging position directing work by gravity toward the discharge opening, and a cover grid for the exhaust opening located to receive and direct discharging work to the discharge opening, the exhaust opening having an entrance chamber extending beneath said grid upward sufficiently to lap the lowermost portion of the movable wall of the work container when said wall is in the discharging position.

5. The combination of a hopper having an intake, a work discharge chute therefor, means for normally closing said chute against pressure exhaust, means preceding the intake for delivering drying media under pressure to said hopper in the direction of advance of work toward the discharge chute, an exhaust pipe communicating with the chute above the closure thereof, a work container in said hopper, and means for directing discharging work from said work container across the line of exhaust of drying media on its way to the exit of the chute.

6. The combination of a pressure housing having an intake, a hood located above the

housing and movable to and from a position in connection with said housing, means preceding the housing intake and discharging into the hood for delivering a hot blast through the hood into the housing, a reticulated work container in the path of said blast, means for movably supporting a section of said work container for enabling the same to be moved to and from a discharging position, the housing having a work discharge opening below the reticulated container, and means for controlling exhaust of the hot blast for maintaining a pressure in the housing above mere passing contact of the blast with the work.

7. The combination of a pressure housing, a hood movable to and from a position in connection with said housing, means preceding the hood for delivering a hot blast through the hood into the housing, a reticulated work container in the path of said blast, means for movably supporting a section of said work container for enabling the same to be moved to and from a discharging position, a discharge chute for the housing below the work container and means for controlling exhaust of the hot blast for maintaining a pressure in the housing above mere passing contact of the blast with the work.
